[57] CLAIM

The ornamental design for a sunglasses case, as shown and described.

DESCRIPTION

FIG. 1 is a front perspective view of the sunglasses case of the present invention showing our new design;

FIG. 2 is a front perspective view thereof with the top of the sunglasses case being disposed in an open orientation;

FIG. 3 is a top plan view thereof;

FIG. 4 is a bottom plan view thereof;

FIG. 5 is a front elevational view thereof;

FIG. 6 is a side elevational view;

FIG. 7 is a rear elevational view thereof; and,

FIG. 8 is a side elevational view thereof opposite the side shown in FIG. 6.
